Primary Examiner—M. N. Pandozzi**[57] CLAIM**

The ornamental design for a double dose coffee maker, as shown and described.

DESCRIPTION

FIG. 1 is a front elevational view of the double dose coffee maker showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The cord with plug in FIGS. 1, 2, 5 and 6 are shown broken away for ease of illustration.
